UNITED STATES PATENT OFFICE.

AUGUSTIN I. AMBLER, OF WASHINGTON, DISTRICT OF COLUMBIA, ASSIGNOR
TO THE INTERNATIONAL VAPOR FUEL CARBON IRON AND MANUFACTURING COMPANY, OF SAME PLACE.

IRON-PUDDLING AND GAS-GENERATING APPARATUS.

SPECIFICATION forming part of Letters Patent No. 247,984, dated October 4, 1881.

Application filed August 2, 1880. (No model.)

To all whom it may concern:

Be it known that I, AUGUSTIN I. AMBLER, a citizen of the United States, residing at Washington, in the county of Washington and District of Columbia, have invented certain new and useful Improvements in Iron-Puddling and Gas-Generating Apparatus; and I do hereby declare the following to be a full, clear, and exact description of the invention, such as will 5 enable others skilled in the art to which it appertains to make and use the same, reference being had to the accompanying drawings, and to letters or figures of reference marked thereon, which form a part of this specification.

15 My invention relates to improvements in apparatus for puddling and otherwise treating iron and steel, and for generating gas or vapor from petroleum and its products, and mingling therewith superheated steam so as to form a 20 hydrocarbon vapor for use in such apparatus in heating the same and the metal placed therein; and the objects of my improvements are, first, to provide a suitable furnace for puddling iron and for reheating the blooms or bars; 25 second, to provide an improved apparatus for generating gas or vapor from petroleum and its products, and for mingling therewith superheated steam, and at the same time and by the same operation to produce an oil of low specific gravity (Baumé scale) suitable for use as 30 a lubricant and for other purposes, said gas-generating apparatus being combined with the puddling and reheating furnace and being the means by which fuel is furnished therefor; third, to provide suitably-constructed devices and combinations thereof for producing the results named. I attain these objects by the mechanism illustrated in the accompanying drawings, in which—

40 Figure 1 is a longitudinal section of the apparatus, showing the brick-work in which it is inclosed, a steam-generator, two gas-generators, a heating-furnace for use in starting the operation, a puddling and reheating furnace, and pipes and passages for connecting the different parts of the apparatus. Fig. 2 is a transverse section on line $x-x$ of Fig. 1, showing the steam-generators and other parts in position for use. Fig. 3 is a transverse section on line $y-y$

of Fig. 1, showing the gas-generators; and Figs. 40 4 and 5 are sections showing the construction of parts of the gas-generators.

Similar letters and figures refer to similar parts in the several views.

In constructing furnaces and gas-generators 55 of this character and in providing for their joint use there is formed a receptacle, A, for the parts, made of bricks or of any other suitable material, it being supplied with a chamber or furnace, A', in which there is placed a pan or reservoir, A², for the reception of the iron or other material to be puddled. This pan or reservoir rests upon balls of metal so as to allow it to expand freely in all directions, and has underneath it an air-chamber for the circulation of air beneath it, to prevent it from becoming too highly heated. This pan is, by preference, made circular in form, but any other form may be adopted if found desirable.

For conducting the flame from the burners 70 to the puddling-furnace, flues A³ A³ are provided, as shown in Figs. 1 and 2, they passing over bridge-walls, as shown in Fig. 2, and being deflected downward upon the iron by the curves formed in the arch of the furnace.

From the rear end of furnace A' there extends a flue, A⁴, which passes upward to a chamber, B³, in which are placed pipes B² B², which are for the passage of hot air or superheated steam. After passing over a bridge-wall beneath chamber B³ the flame and heated products of combustion pass down through the flue or passage B⁴ and into a reheating-furnace, B, in which is shown a pile of bars or billots of iron, B', which are supposed to be 80 undergoing the reheating process. From the furnace the heat passes to the flues C', which extend around and between the gas-generators D and E, and thence to a flue, C², underneath the steam-generator F, soon to be described, 90 a portion of said heated products passing through flues or tubes placed in such steam-generator, from which point they pass into the chimney and are delivered into the atmosphere.

For the purpose of connecting the chambers A', B, and B³ with the flues C', and for the admission of air thereto, small flues or pipes a a

are formed or placed in the brick-work in the manner shown, whereby air, either heated or cold, may be admitted into said chambers and pass into the furnaces and flues of the apparatus, and is thus made to aid combustion therein. The passages leading to the puddling and reheating furnaces are supplied with the requisite doors for closing them and preventing the egress of heat at these points, and also the ingress of too much cold air.

As a means of generating gas or vapor from petroleum and its products for use in the furnaces above described, there are provided two or more gas or vapor generators, D and E, which are placed in flue C', leading from the iron-furnaces to the steam-generators. These gas-generators are arranged one above the other, they being connected together by suitable pipes for the passage of steam and gas or vapor from the oil, and they consist of two double cylinders, D and E. Within the cylinder D there is placed a smaller one the outer diameter of which is so much less than the interior diameter of the outer one as to leave a space or steam-chamber between them sufficiently large for the free circulation of superheated steam. These cylinders have each a head bolted upon one of their ends, the joints being ground so as to cause them to be steam and gas tight, they being held in position by means of yokes and set-screws, as clearly shown in Fig. 3 of the drawings.

The generators are connected together by a pipe which extends from one to the other, its ends communicating with the steam-spaces between the outer and inner cylinders in each of them.

Within the interior cylinder of generator E there is placed a gas or vapor receptacle, E', which consists of a short cylinder or box, having a perforated upper surface, through which the gas or vapor escapes into said interior cylinder, where it is adheated by a coil of pipe, E², through which superheated steam is caused to pass, the gas escaping from the said cylinder to the burners through the pipe I, which conducts it to the desired locality.

From the receptacle E' there extends downward and into the interior cylinder of generator D a pipe, D', upon the lower portion of which there is placed a trap, having in it a cock for drawing off any oil that may collect therein. From this trap the pipe D' extends upward to near the upper wall of the cylinder in which it is placed, its upper end being perforated, so that the gas or vapor collecting in the chamber in the lower interior cylinder may pass into it out into the receptacle E', and thence through the perforations in the top to the upper inner cylinder for use.

In order that the chamber in which pipe D' is placed shall receive gas or vapor only, and that the body of oil which is allowed to collect in the lower portion of the interior cylinder of the generator D shall not enter said chamber, there is provided a plate or diaphragm, D³, which fits tightly in the cylinder, thus pre-

venting the flow of oil into it. This plate or diaphragm is perforated near its upper surface, so that the gas or vapor which rises to the upper portion of the cylinder may pass freely into the chamber.

For the purpose of conducting the oil to be vaporized to the interior cylinder of generator D there is provided a pipe, D⁴, which extends through one end of each of the cylinders composing the generator D, and passes inward to and through the plate or diaphragm above alluded to, its inner end being closed by a plug, so that no oil can pass that point. This pipe is to be perforated, so that the oil in entering it shall be allowed to pass out upon the coil D², which, acting in conjunction with the steam-heated surface of the cylinder, will convert a large proportion of it into gas or vapor, which will pass off as above described, the remaining portion of the oil, or that portion not vaporized, being drawn off and used as a lubricant or for other purposes where an oil of low specific gravity (Baumé scale) is required.

For superheating steam for use in this apparatus a coil of pipe, d, is placed around the generator D, one of its ends being connected with steam-generators, soon to be described, and its opposite end to a pipe or pipes leading to the interior of the gas-generators, the heat for superheating the steam in said coil being derived from the flame and heated products of combustion passing through the flue c' of the furnace.

Within the inner cylinder of the upper gas-generator there is placed a coil of pipe, E², through which steam passes from the space between the two cylinders, it having previously traversed the space between the cylinders of the lower generator, this coil of pipe, as before remarked, serving to adheat the gas or vapor.

For the purpose of supplying the gas or vapor generators with oil there is employed a steam-driven pump, G, which is connected by a pipe, G', with an oil-supply tank, not shown, but which may be located at any safe distance from the furnace, and under ground if desirable for safety. From this tank the oil is taken by the pump and forced through a pipe, F⁴, into a tank or pipe of large dimensions, designated as F'. Oil is forced into this pipe until it has attained such pressure as to cause it to flow through a pipe, F², into the pipe D⁴, and into the interior of the inner cylinder of the generator D, the quantity thus passing being regulated by a valve, 7, placed in said pipe.

As a further means of injecting the oil the upper end of pipe F' is connected with the steam-generator by means of a pipe provided with a valve, 3, so that steam may be let into pipe F' at or near the top of the body of the oil, which will thus be forced to its destination by steam pressure, it being regulated by the valve 3.

For the purpose of utilizing as far as possible the heat used in the puddling and reheating furnaces, and thus producing the best economic results, there is combined with the other

- parts of the apparatus one or more steam-generators, F, which, by the utilization of the heat escaping from such furnaces, are made to generate all of the steam required for the vaporization of the oil used in the gas or vapor generators and for driving the steam-pump, and by increasing the number of steam-generators may be made to furnish a large surplus of steam for other purposes.
- 10 The steam for driving the pump G and for vaporizing the oil is taken from the dome of one of the steam-generators through valve 2, passes through pipe H and valves 4 4, by which the amount may be controlled, a portion passing through pipe F³ and valve 5 to the pump.

15 It is sometimes desirable to use steam that has not been superheated—as, for instance, in starting the operation of the apparatus or at times when it is only necessary to use a small amount of vapor—and to provide for occasions of this kind a pipe, H', is connected to one of the steam-generators, it being supplied with valves 10 10 and leading down to and being connected with a pipe leading to the chambers 25 and coils of pipe in the gas-generators, the arrangement being such that by closing the valves which allow steam to pass through the superheating-coil and opening those in pipe H' saturated steam may be used to the exclusion of 30 the superheated; or, should the heat in the furnace C' be so intense at any time as to superheat the steam to too great an extent, by properly manipulating the valves the two kinds of steam may be mingled in the gas or vapor 35 generators, and thus the temperature be regulated to suit the different circumstances.

For taking the gas or vapor from the generators and conducting it to the burners a pipe, I, is provided, which is supplied with a valve, 40 14, (shown in Fig. 2 of the drawings.) To the outer end of this pipe two double T-pieces are secured, from the lower apertures in which pipes I' I' lead to the burners I² I², placed in the flues leading to the puddling-furnace, each 45 of these pipes being supplied with a valve, 12, for controlling the amount of gas that shall pass through it.

As a means of conducting steam from the coil in which it is superheated to the chambers and coils of the gas or vapor generators pipes I³ are provided, the amount of steam passing them being controlled by valves 6, 6, and 9. For conducting superheated steam into direct contact with the body of the oil in 50 the gas or vapor generators there is provided a pipe, I⁴, the amount of steam passing through it being controlled by a valve, 8, by which means the amount of steam which is allowed to mingle with the gas or vapor arising from 55 the oil is regulated, and consequently the character of the gas as it escapes from the apparatus or when it arrives at the burners is determined.

This apparatus is provided with oil and 60 steam and gas gages for showing pressure, and with pyrometers for showing the tempera-

ture of the steam and gas; but as these parts, when separately considered, form no part of the invention claimed in this application, they need not be particularly described here, their 70 combinations and arrangement being clearly shown in Fig. 2 of the drawings. The apparatus is also provided with a glass gage, which is attached to the gas or vapor generators for the purpose of showing the condition of the 75 oil in the lower one and for determining when the same should be drawn off, it being effected by means of a pipe supplied with a valve, 13, (shown in Fig. 2.)

The method of operating this apparatus is 80 as follows: The parts being constructed and arranged substantially as shown, a fire is kindled in the furnace C and is kept burning until steam of the required temperature is generated, when valves 2 and 4 are opened, 85 which will allow it to enter the superheating-coil surrounding the lower gas-generator; and when the pyrometer J shows a temperature of, say, 500° Fahrenheit, the steam is let into the chambers and coils of pipe in the gas-generators; and as soon as the proper amount of heat is obtained therein it is let into the inner cylinder of generator D, which vaporizes the 90 oil to such an extent as to fill the gas-chambers. The superheated steam is then let into 95 the body of the oil in the generator D, by which means the requisite amount of pressure will be obtained. When the gas-pressure gage shows a pressure of, say, ten pounds less than the gage connected with the steam-generator, 100 or, say, eighty pounds, and the pyrometer shows from 300° to 400° Fahrenheit, the gas or vapor is ready for use. The valves 12 12 are now opened slightly and the gas is permitted to flow to the burners, where it is ignited by any suitable means, the flames and heat passing to the puddling and reheating furnaces, it being regulated according to the kind of work to be done, such effect being produced by the regulation of the quantity of gas 110 burned.

For the purpose of collecting any oil that may result from the condensation of gas or vapor in the pipe leading from the gas or vapor generators to the burners, there is provided a 115 tank, L, a cock being placed in the pipe for drawing it off into said tank.

I do not claim in this application the combination of horizontally-arranged double cylinders having a steam-space between them, 120 such cylinders having coils of pipe in them; neither do I claim here the combination of the removable heads with the cylinders; neither do I here claim any part of the apparatus shown for generating gas from petroleum or 125 other hydrocarbons, or for decomposing steam—as such parts are shown, described, and claimed in an application filed by me on the 2d of August, 1880, and designated as "Case B," for an apparatus for the production of gas or vapor from 130 petroleum.

Having thus described my invention, what

I claim, and desire to secure by Letters Patent, is—

1. In an apparatus for generating gas or vapor from petroleum and other hydrocarbons, and for puddling and reheating iron and steel, the combination of the gas or vapor generators D and E, constructed substantially as herein described, one or more steam - generators for generating steam by the waste heat from the furnace, a puddling and a reheating furnace, said combination to include the necessary pipes for conducting the gas from the gas-generators to the furnaces, and flues for conducting the flame and heat from the furnace to the steam-generator, all substantially as described.
2. The combination of the puddling-furnace A', reheating-furnace B, the flues A³ A³ and C', the gas or vapor generators, and one or more steam-generators, F, all arranged for operation substantially as described.
3. In an apparatus for generating gas or vapor from petroleum and for puddling and reheating iron and steel, the combination of the

preliminary furnace C, puddling-furnace A', reheating-furnace B, flues or passages C', the 25 gas or vapor generators D and E, and one or more steam-generators, F, the parts being constructed and arranged for joint operation substantially as described.

4. In combination with the furnaces A' and 30 B, the circulating tubes or flues a a, and the flue C², for the passage of air and a portion of the heat from said furnaces, substantially as and for the purpose set forth.

5. The combination of the puddling-furnace 35 A', the reheating-furnace B, the gas or vapor generators D and E, gas-pipes I', gas-burners I², and flues or passages A³, the parts being arranged for joint operation substantially as set forth.

In testimony whereof I affix my signature in presence of two witnesses.

AUGUSTIN I. AMBLER.
